UNITED STATES PATENT OFFICE.

EDWARD P. DONNELL, OF CHICAGO, ILLINOIS.

MACHINE FOR CUTTING INDEXES.

SPECIFICATION forming part of Letters Patent No. 399,250, dated March 12, 1889.

Application filed March 9, 1886. Serial No. 194,658. (No model.)

To all whom it may concern:

Be it known that I, EDWARD P. DONNELL, residing at Chicago, in the county of Cook and State of Illinois, and a citizen of the 5 United States, have invented a new and useful Improvement in Machines for Cutting Indexes, of which the following is a full description, reference being had to the accompanying drawings, in which—

10 Figure 1 is a front elevation with the standard or support broken; Fig. 2, a side elevation with the standard or support and the connecting-rod broken; Fig. 3, a top or plan view with the standard carrying the cutting-tool in section, the tool not being shown; Fig. 4, a perspective view showing the manner of cutting the index or other article; Fig. 5, a detail of the cutting-tool for making the steps; Fig. 6, a detail showing the position of the 20 guides for trimming the corners; Fig. 7, a detail of the tool for trimming the corners; Fig. 8, a detail of a punch.

This invention has for its object to construct a machine by which the cutting out of 25 portions of sheets of paper to form index steps or removing pieces of a book or other article for indexing purposes can be readily and quickly accomplished, and have the steps which are formed of a uniform character in 30 regard to size and the line of cut, the machine being also adapted to receive other tools for trimming the corners or punching holes through a number of leaves or sheets of paper; and its nature consists in the several 35 parts and combinations of parts hereinafter described, and pointed out in the claim as new.

In the drawings, A represents a standard or upright, having at its lower end a base portion, A', which can be secured to a floor or other support, and having, as shown, its upper end, A'', enlarged to furnish a support for the table or bed on which the article to be operated upon is placed.

40 B is the bed or support attached to the top A'' in any suitable manner, and of the dimensions required for the size of machine.

C is a sliding plate having on its under side a dovetail, b, to fit a dovetailed recess, a, in 45 the table or support B, by which means the

plate is connected with the table, so that it is free to slide back and forth.

D is a stem having on its outer end a hand-wheel, D', and having its inner end suitably journaled in a box or bearing, D'', attached 55 to the under side of the table B at the front edge. The front edge of the sliding plate C is provided with a rib or projecting flange, c, the upper edge of which is provided with a scale, and the under edge has thereon a rack, 60 with which meshes a wheel, d, on the stem D, so that by turning the stem through the hand-wheel D' the wheel d and rack on the rib c operate to move the plate C back and forth, and the required amount of movement is regulated by a pointer, d', which coacts with the scale on the upper side of c.

E is a bar, the ends of which receive studs or pins e, extending up from the slide C, and receiving nuts e', by means of which the bar 70 E can be forced down to firmly clamp the article placed between it and the top of the slide.

F is a series of sheets of paper, which are to be provided with steps f to form an index. 75

G represents guides, each having a vertical portion, g, and a horizontal portion, in which is a slot, g', for the passage of a set-screw or bolt, g'', by means of which the slides can be adjusted to regulate the amount of inward 80 cut for the index or other article, and be locked firmly in position by the set-screws g'' when the proper adjustment has been made.

H is the tool for cutting the steps for an index, which tool, as shown, has a wide cutting-edge, h, and a narrower cutting-edge, h'.

I is a bar, the lower end of which receives the stem of the cutting-tool H, which is locked firmly in place by a set-screw, i, or other suitable device.

J is a removable cap, forming one half of the box for the sliding bar I, and connected with the other half, J', of such box by ears j on the cap J, which coincide with projections j' on the portion J', through which ears j and into the projections j' bolts or screws j'' are passed, by which means the cap J is readily removed in case it is desired to remove the sliding bar I, and by making the support for the bar in two parts a better and more accu- 90 95 100

rate fit between the reciprocating bar I and its support can be made.

K is an arm, with which is formed the portion J' of the support for the bar I, and, as shown, this arm at its lower end has a base or flange, K', through which bolts or screws k pass for attaching the arm to the bed B.

L is an upright or post extending up from the arm K and formed therewith in the construction shown.

M is a cross-bar, one end of which is pivoted by a suitable pin or pivot, l, to the upper end of the standard L, and the other end is pivoted by a suitable pin or pivot, m, to the upper end of the bar I.

N is a connecting-rod, the upper end of which is screw-threaded to receive a nut, n, and this upper end is connected with a fork, N', which is attached to the bar M by a suitable pin or pivot, n', and the lower end of the rod is connected with a fork, N''. This rod N passes through the arm K, and a nut, n, is arranged to strike against the top of the arm K, and thereby limit the downward thrust of the bar I, and consequently the stroke of the cutting-tool H.

O is a foot treadle or lever, the attached end of which is connected to a standard, O', by a suitable pin or pivot, o, the standard O' being attached to the base-plate A' by bolts or screws o', and to this foot treadle or lever O, back of the standard O', is attached the fork N'' by a suitable pin or pivot, n''.

P is a coiled spring, one end of which is connected with the foot treadle or lever O and the other with a hook, p, projecting out from the standard A.

Q is a foot-rest attached to the free end of the treadle or lever O.

The operation is as follows: The leaves or sheets for the index F are placed beneath the clamping-bar E, and by means of such bar and the set-nuts e' clamped firmly to the slide C, before which the gages or guides G are adjusted for the required depth of incut, and in putting the leaves beneath the clamp they are reversed in position from that which they will occupy when the index is complete—that is, the bottom of the index will be the top leaf or leaves. The slide C is carried back for the required width of cut for the first step, and the leaf or leaves which form the bottom of the index are turned back, as shown in Fig. 4, when the operator, placing his foot on the lever or treadle O, forces down such lever or treadle, carrying down the rod N and the outer end of the bar M, forcing the slide-bar I down and giving the stroke to the cutting-

tool H, to force such tool through the remaining leaves of the index, so that when the leaves which have been turned back are dropped down a step will be formed. The tool is then withdrawn by the operator removing his foot from the treadle or lever O, which leaves the spring P free to throw the lever up and through the rod N and bar M carry up the bar I and the cutting-tool H. Then the number of leaves for the next step are turned back and the cutting-tool again forced down through the lever or treadle O, forming the next step on those leaves which have been turned back, and this operation is repeated until the full number of steps have been formed. The steps are regulated in size by the scale on c, in connection with the pointer d', through which the advance of the slide C from the wheel d and rack-bar on c is regulated to a uniformity. The leaves at the completion of the cutting are removed from the table by loosening the clamping-bar E, when they can be turned over, and a stepped index will be had on which can be placed letters or other references, as may be desired.

The machine will be found useful in cutting indexes for letter-files, index-books, or other books where steps are required, and for cutting leaves and books for the purpose of forming a step or inset to receive reference-marks.

The machine when used for indexes can also be made to cut the holes in the index-leaves for the fastening cord or wire by removing the tool H and substituting therefor the punch H', (shown in Fig. 8,) and in case it is desired to round the corners of the leaves which have been cut it can be readily and quickly done by turning the guides G, as shown in Fig. 6, to receive the corner of the index or book as a whole, and then using a tool, H'', as shown in Fig. 7, by means of which the corner of the index or book can be trimmed rounding, as shown in Fig. 6.

What I claim as new, and desire to secure by Letters Patent, is—

In an index-cutting machine, the bed B, having recess a, sliding plate C, having dovetail b on its under side to enter the recess a, and side flange, c, provided with a scale, and a rack on its upper and under faces, respectively, in combination with the rod D, gear-wheel d, and pointer d', substantially as and for the purpose specified.

EDWARD P. DONNELL.
